UNITED STATES PATENT OFFICE.

OWEN E. SONNE, OF REPRESA, RUSSELL W. PROCTOR, OF DAVIS, AND ARTHUR E. MILLER, OF SACRAMENTO, CALIFORNIA.

IMPRESSION STAMP.

1,411,892.

Specification of Letters Patent.

Patented Apr. 4, 1922.

Application filed August 1, 1921. Serial No. 488,911.

To all whom it may concern:

Be it known that we, OWEN E. SONNE, RUSSELL W. PROCTOR, and ARTHUR E. MILLER, citizens of the United States, residing 5 as follows: said SONNE and MILLER residing, respectively, at Represa and Sacramento, in the county of Sacramento, and said PROCTOR residing at Davis, in the county of Yolo, all in the State of California, have invented 10 certain new and useful Improvements in Impression Stamps, of which the following is a specification.

This invention relates to presses or stamps for impressing or embossing an indicating 15 design upon paper and the like, and has particular reference to the provision of a pair of improved die members so arranged as to contact simultaneously with the work placed therebetween to form the desired impression.

20 An object of this invention is to provide a device of this character comprising a pair of coacting die members, each provided with a fixed impression surface and a movable impression surface capable of adjustment with 25 respect to the fixed surface, for selectively indicating different characters, amounts, dates and the like, and to provide means for insuring the proper positioning of the movable surface with respect to an indicating 30 mark made by the fixed die surface.

A further object of this invention is to 35 provide a device of the above mentioned character capable of use for impressing upon a check or other monetary instrument the design of peculiar characteristics set forth in our copending application Serial Number 486,406, filed July 21, 1921, to indicate the value of the instrument and to further indicate whether or not the same has been 40 altered from its true amount.

45 A further object of this invention is to provide a device of the above mentioned character that is simple in construction, inexpensive to manufacture, convenient in use and strong and durable.

In the accompanying drawings, forming 50 a part of this specification and in which like numerals are employed to designate like parts throughout the several views,

55 Fig. 1 is a central longitudinal sectional view through a press embodying our invention showing the die members in separated position,

Fig. 2 is a horizontal sectional view on 55 the line 2-2 of Fig. 1,

Fig. 3 is a fragmental view of a check or other paper impressed with our device,

Fig. 4 is a perspective view of the plunger cap, and,

Fig. 5 is a fragmental plan view showing 60 the indicating notch.

Referring to the drawings, wherein for the purpose of illustration is shown a preferred example of our invention, the numeral 6 designates the base or body of our 65 improved press having at one side thereof an upright shaft 7 on which is rotatably mounted a pinion 8. A suitable longitudinal opening is provided in the base, and inserted within said opening are a pair of 70 coacting die members, one of said die members being disposed in the upper portion and the other die member being disposed in the lower portion thereof. The said die members are formed with any desired wording 75 or symbols, the markings being embossed on the male die and depressed in the face of the female die for intermeshing engagement when impressing a sheet of paper inserted between the members.

The lower die member comprises a central stationary die 9 provided with a downwardly tapered outer edge, and an outer rotatable surface or annulus 10 having a tapered inner edge and provided on its periphery with gear teeth 11, meshing with the pinion 8. The central die surface 9 is rigidly secured to the base by a suitable fastening means 12 while the outer rotatable die surface is free to rotate about the stationary central die surface but is held against vertical displacement by reason of the tapered edge of the central die surface 9, and the corresponding taper of the inner edge of the annular die surface 10.

The upper die member likewise comprises a fixed central die surface 13 having an upwardly tapered outer edge, and an outer rotatable die surface or annulus 14 having a tapered inner edge and provided on its periphery with gear teeth 15 meshing with pinion 8. By reason of the upwardly tapered edge of the fixed die surface 13 and the corresponding taper of the inner edge of the annulus 14, the latter is free to rotate about the central die surface but is held against vertical displacement. This upper die member is secured to a plunger 16 which is vertically reciprocable to bring the upper die member into intermeshing engagement 110

with the lower die member. Arranged with in sockets at diametrically opposite sides of the reciprocating plunger are a pair of spiral compression springs 17 which exert 5 upward pressure on the ears 18 of the plunger cap 19 to normally hold the coacting die members out of contact. An operating handle 20 is pivotally connected to the body 6 of the press as shown at 21 and is provided 10 with a cam surface contacting with the plunger cap 19. It is thus obvious that a downward movement of the handle 20 about its pivot 21 will impart a downward movement to the plunger 16 and will force 15 the upper die member into intermeshing engagement with the lower die member and that upon the releasing of the handle, the springs 17 will serve to raise the upper die member out of engagement, leaving a sufficient space between the die members for the 20 insertion of the paper upon which the impression is to be made.

The rotatable die surface 14 of the upper reciprocating die member has stamped or 25 otherwise placed on the upper surface thereof a series of characters, numerals or the like corresponding to those on the lower side of the die surface. Any rotation of the annular die surface 14 will cause a rotation of 30 the pinion 8 about its shaft 7 and this rotation will be imparted to the companion rotatable die surface 10 of the lower die member so that the two rotatable die surfaces move in unison. To enable one to quickly 35 and accurately determine the relative position of the characters carried by the rotatable die surfaces with respect to the indicating mark 22 forming a part of the impression made by the non-rotatable die surfaces, we provide a sight opening or notch 40 23 through which each separate character on the upper side of the rotatable die surface 14 may be readily seen. To insure the proper positioning of the characters on the rotatable 45 die surfaces with the indicating mark 22, a spring pressed ball or ratchet 24 is radially arranged with respect to the pinion 8 and enters the space between the teeth thereon so that the selected character is always properly 50 aligned or centered with respect to the indicating notch 22 and sight opening 23.

In the accompanying drawings, we have 55 illustrated the shank constructed to impress upon a check or other monetary instrument a design of peculiar characteristics, this design to overlie a portion of the signature of the drawer of the instrument and to entirely overlie the numerals on the instrument which indicate the amount for which it is 60 drawn. One of the fixed surfaces 9 or 18 is provided with a male die and the other with a female die, the dies bearing a suitable design such as shown in Figs. 2 and 3 and being further provided with means for embossing or depressing the indicating mark 65

22 upon the surface of the paper. One of the movable die surfaces 10 or 14 is provided with a male die and the other with a female die, the dies bearing a series of arbitrary numerals or the like which are associated with 70 the design of the fixed die surfaces in such a manner as to form a code which may or may not be secret, which when the impression is made on the paper will indicate at once the value of the paper and will further indicate 75 whether or not the same has been altered from its true amount. In order to selectively associate a particular numeral in proper relation to the indicating mark 22 on the central die surfaces to indicate the amount for 80 which the paper is drawn, it is merely necessary to rotate either the rotatable die surfaces 10 or 14 until the desired character appears at the sight opening 23. This rotation of either rotatable surface causes a corresponding movement of the other so that the entire die assembly is in proper position for 85 impressing the paper. The paper is then inserted between the die members and a downward movement of the handle 20 makes the 90 desired impression on the paper as shown in Fig. 3. It is to be noted that the term "upper die member" is used to designate that portion of the stamp formed by the fixed part 13 and the movable part 14, and the 95 term "lower die member" is used to designate the corresponding fixed and movable parts 9 and 10.

While we have chosen to illustrate our stamp made to impress an improved design 100 upon checks or other monetary instruments for preventing the fraudulent raising of the same, this invention is by no means limited to this specific use.

In short the device is capable of use in 105 any instance where stationary and movable dies are required to impress a mark upon paper or the like, one portion of the dies remaining constant while the other portion is capable of adjustment with respect to the 110 constant portion for selectively indicating varying amounts, dates, quantities and the like.

It is to be understood that the form of our 115 invention herewith shown and described is to be taken as a preferred example of the same and that various changes in the shape, size and arrangement of parts may be resorted to without departing from the spirit of the invention or the scope of the subjoined claims. 120

Having thus described our invention, what we claim as new and desire to secure by Letters Patent is:—

1. In a device of the character described, the combination of a pair of coacting die members each comprising a fixed impression surface and a movable impression surface, and means for forcing said members into intermeshing relation.
2. In a device of the character described,

130

- the combination of a pair of coacting die members each comprising a stationary die surface and a movable die surface, means for transmitting the movement of either 5 movable die surface to its companion movable die surface, and means for forcing the die members into intermeshing relation. 3. A device of the character described, comprising a pair of adjacent coacting die 10 members, each comprising a fixed section and a movable section, an indicating mark carried by the fixed sections, and means for indicating the relative position of the movable sections with respect to the indicating 15 mark. 4. A device of the character described comprising a base, a pair of movable coacting die surfaces, a stationary indicating mark, a series of index characters on one of 20 the movable dies corresponding to the impression characters on the movable die surfaces, and an indicating opening in the base through which the index characters may be viewed for the proper positioning of the 25 impression characters with respect to the indicating mark. 5. A device of the character described comprising a base, a rotatable pinion journaled in the base; a pair of movable coacting die surfaces provided with teeth meshing 30 with the pinion whereby movement of one die surface imparts a corresponding movement of the companion die surface, a series to index characters on one side of one of the 35 movable die surfaces corresponding to the impression characters on said movable surfaces, a stationary fixed indicating mark, and an indicating opening in the base through which the index characters may be 40 viewed for the proper positioning of the impression characters on the movable die surfaces with respect to the fixed indicating mark. 6. A device of the character described 45 comprising a pair of coacting impression members each comprising a central disk whose periphery decreases in diameter from the impression surface to form a tapered outer edge, and an annular die section whose 50 width increases from the impression surface to form an internal taper which corresponds to the taper of the central section, whereby the two concentric die surfaces are held in the proper plane but are free to rotate with respect to each other. 7. A device of the character described, comprising a pair of normally spaced co- 55 acting impression members each comprising a central non-rotatable section and an outer rotatable annular section, means for normally maintaining the members in spaced relation, and an operating handle for forcing said members into intermeshing relation to impress a sheet placed therebetween. 8. A device of the character described comprising a pair of coacting impression die members each comprising a central non-rotatable section for making a suitable impression including an indicating mark and 60 an outer rotatable annular die section carrying a series of arbitrary characters any one of which may be associated with the indicating mark, means for indicating the relative position of the individual characters with respect to the mark, and means for forcing the die members into intermeshing relation to impress a sheet placed therebetween. 9. A device of the character described, comprising a pair of normally spaced coacting die members, each comprising a central non-rotatable section for making a suitable impression including an indicating mark, and an outer rotatable annular die 65 section carrying a series of arbitrary characters any one of which may be associated with the indicating mark; means for transmitting the movement of either rotatable section to the other rotatable section to associate a desired character with the indicating mark; and means for insuring the proper alignment of the selected character with the indicating mark. 10. A device of the character described comprising a base, a pinion rotatably journaled in said base, a pair of coacting movable die surfaces carrying a series of arbitrary characters and provided with teeth meshing with the pinion whereby movement 70 of either die surface imparts a corresponding movement to its companion surfaces, an indicating mark with which any character on the movable die surfaces may be associated, and a ratchet engaging the pinion 75 to control the movement of the same to insure the proper alignment of the selected character with the indicating mark. In testimony whereof we hereunto affix our signatures. 110
